UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

ELECTRIC SWITCH.

Application filed May 20, 1925. Serial No. 31,649.

The invention relates to improvements in electric switches.

The object of the present invention is to improve the construction of electric switches of the snap toggle type and to provide a simple, practical and efficient electric switch of this character which will be strong and durable and which will have a quick make and break and be capable of positively maintaining itself in its on and off position.

With these and other objects in view, the invention consists in the construction and novel combination and arrangement of parts hereinafter fully described, illustrated in the accompanying drawings and pointed out in the claim hereto appended, it being understood that various changes in the form, proportion and minor details of construction, within the scope of the claim, may be resorted to without departing from the spirit or sacrificing any of the advantages of the invention.

In the drawings:

Figure 1 is a side elevation of a lamp socket equipped with an electric switch constructed in accordance with this invention.

Fig. 2 is a longitudinal, sectional view of the same.

Fig. 3 is a plan view of the switch mechanism, the cap of the outer shell being removed.

Fig. 4 is a reverse plan view of the insulating base illustrating the arrangement of the center and stationary switch terminals.

Fig. 5 is a detail view of the supporting bracket of the switch mechanism.

Fig. 6 is an elevation of the insulating base.

Fig. 7 is a horizontal sectional view on the line 7—7 of Fig. 2.

In the accompanying drawing in which is illustrated the preferred embodiment of the invention, the electric switch is shown applied to a lamp socket equipped with a metallic outer shell 1 of the ordinary construction and having an insulating lining tube. The metallic shell or casing 1 consists of a body portion and a removable cap 3. The outer shell is reduced at its intermediate portion to provide a shoulder or seat for supporting an insulating base 4 constructed of a single piece of suitable insulating material and molded in the form shown and provided with a central vertical recess forming an intermediate compartment

or space 5 for the reception of the switch mechanism. The switch receiving space or compartment is formed by upwardly extending substantially parallel walls and it is open at the top and ends as shown. The walls 6 are approximately straight and are recessed at their inner and outer faces at 7 and 8 at opposite sides of the insulating base as clearly shown in Fig. 3 of the drawings to lighten the construction and reduce the amount of insulating material and at the same time provide an enlarged intermediate switch receiving space and exterior recesses or spaces for the binding terminals 9. The insulating base is circular and fits the standard shells or outer casings and it is provided exteriorly of the walls adjacent the binding terminals 9 with lugs 10 recessed at 11 adjacent the binding terminals for the double purpose of providing air spaces and for reducing the amount of insulating material. The lugs 10 extend upwardly from the bottom circular portion of the insulating base and terminate midway between the top and bottom of the spaced side walls.

The switch mechanism comprises in its construction an approximately U-shaped supporting bracket 12 composed of spaced sides and a connecting horizontal bottom portion 13. The sides are provided intermediate of the top and bottom of the bracket with aligned openings for the reception of a pivot pin 14 and have upper and lower relatively narrow arms 15 and 16 extending outwardly from the sides in the planes of the same and then curved downwardly and upwardly respectively, toward each other as clearly illustrated in Fig. 5 of the drawings to form stops for an operating lever 17 and an oscillatory switch member 18. The operating lever consists of a handle portion 19 of molded or other suitable material and an approximately U-shaped body portion having spaced sides and a connecting transverse portion provided with a shank 20 which is embedded in the handle. The spaced sides of the operating lever are provided with perforations to receive the transverse pivot pin 14 and they contact with upper and lower inwardly extending lugs 21 of the upper and lower arms 15 and 16. The arms are also provided with outwardly projecting laterally extending terminal lugs 22 located in the crotches formed by the arms and the sides of the bracket for limiting the swing-

ing movement of the switch member 18. The switch member 18 which cooperates with a pair of stationary switch terminals 23 and 24 is approximately U-shaped, being composed of spaced sides and a connecting transverse portion. The U-shaped body portion of the operating lever is arranged between the sides of the bracket 12 and the sides of the switch member 18 are arranged exteriorly of the sides of the supporting bracket and are provided at their inner pivoted ends with bearing recesses 25 approximately L-shaped, forming terminal hooks 26 which engage over laterally extending bearing lugs 27 preferably formed integral with the sides of the supporting bracket by bending portions thereof laterally. By this construction the movable switch member may be readily engaged with and disengaged from the supporting bracket.

The movable switch member is maintained positively in engagement with the switch terminals 23 and 24 and also out of engagement with the same when in off position by a coiled spring 28 disposed on a rod 29 which is secured at its outer end 30 in an opening in the transverse portion of the movable switch member. The inner portion of the rod extends through an opening 31 in a rocking plate 32 having laterally extending pivots or trunnions 33 mounted in aligned bearing openings in the outer ends of the sides of the operating lever. The coiled spring thrusts against an enlargement or head at the outer end 30 of the rod 29 and against the said rocking plate 32 and when the lever is operated by hand and is oscillated, the spring is compressed on the rod until the parts reach a dead center and as soon as the rod is carried beyond the dead center the spring will cause the switch member to snap quickly and reverse its position. It will be seen that the switch mechanism forms a spring actuated toggle and will produce a positive operation of the parts as soon as the inner end of the operating lever is carried beyond the said dead center. A quick and effective throw is thus provided for actuating the oscillatory switch member. The rod on which the spring is mounted is fixed to the transverse portion of the movable switch member and has no longitudinal movement relative to the said member which swings between the upper and lower laterally projecting stop lugs of the arms of the supporting bracket. The spring maintains the hook shaped terminals of the sides of the switch member in engagement with the bearing studs of the supporting bracket and prevents any accidental disengagement of the said hook shaped terminals.

The stationary switch terminal 23 consists of a flexible arm or portion of a plate 34 of copper or other suitable conducting material secured to the lower face of the

insulating base in a recess 35 thereof by means of a screw 36 which also secures one of the binding terminals 9 to the base. Each of the binding terminals consists of an approximately L-shaped plate fitted against the adjacent lug 10 and having a binding screw 37 which cooperates with a projecting portion 38 of the binding terminal to enable one end of a wire to be securely fastened to the binding terminal. The other stationary switch terminal consists of a flexible arm or portion of an approximately L-shaped plate 39 which is secured to the lower face of the insulating base in a recess 40 thereof by means of a hollow rivet 41 or other suitable fastening device which also secures the center contact 42 to the lower face of the insulating base. The insulating base is provided with spaced slots 43 through which the flexible arms or portions of the stationary switch terminals extend so as to project from the bottom portion of the insulating base to cooperate with the movable switch member. The upper ends of the stationary switch terminals are bent outwardly slightly to provide a flared entrance to prevent injury to the stationary switch contacts. The flexible character of the stationary switch contacts will maintain a proper electrical contact between them and the movable switch member. The center contact 42 consists of a plate or piece of copper or other suitable material bent at an intermediate point to form upper and lower sides, the upper side being secured to the insulating base by the said hollow rivet and the lower side being provided with a cup shaped terminal portion 44 presenting a lower convex face for engaging with an electric lamp. The lower contacting portion of the center contact may be readily bent upwardly or downwardly to arrange it in proper position for making a perfect contact. The center contact extends through a central slot 45 of an insulating washer 46 which is fitted against the lower face of the insulating base and is interposed between the same and a flange 47 of a screw shell contact 48. The shell contact and the washer are secured to the insulating base by means of an attaching screw 49 and a screw 50 which secures one of the binding terminals to the insulating base. The binding terminal to which the screw 50 is connected is electrically connected with the shell contact 48 and the other binding terminal is connected by means heretofore described with the center contact 42.

What is claimed is:

An electric switch including a bracket having spaced vertical sides provided with upper and lower relatively narrow arms arranged in pairs and extending from the sides of the bracket in the planes of the said sides and curved downwardly and upwardly re-

spectively toward each other and provided at their extremities with outwardly extending laterally projecting lugs and having at their bases inwardly extending laterally 5 projecting lugs located in the crotches formed by the arms and the sides of the bracket, an operating lever pivotally mounted within the bracket and having spaced sides adjacent the sides of the bracket and 10 arranged to swing between and have their movement limited by the laterally projecting lugs at the bases of the arms, a yoke pivotally mounted on the sides of the bracket at the outer faces thereof and arranged to swing between and have its upward and 15 downward movement limited by the outwardly extending laterally projecting lugs, a rocking plate mounted between the sides of the operating lever, a pin mounted at its terminals on the yoke and the said plate, 20 and a coiled spring disposed on the pin and interposed between the yoke and the plate.

In testimony whereof I have hereunto set my hand.

WILLIAM ILE.
